CHARLES T. BRADY, OF DETROIT, MICHIGAN

LAMP SHADE

Application filed November 19, 1928. Serial No. 320,309.

In my co-pending application, Serial No. 312,423, filed October 15, 1928, I have disclosed a lamp shade equipped to produce a filtered light resembling daylight. This function is accomplished by a closure member in the light-emitting end of the shade and a suitable lens in the closure member. In replacing the lamp within the shade, it is found desirable to remove the closure member, and the object of the present invention is to provide a construction wherein this member is readily removable.

The invention is fully disclosed by way of example in the following description and 15 in the accompanying drawing, in which—

Figure 1 is a perspective view of the lamp shade with the closure member removed therefrom;

Fig. 2 is a perspective view of the closure 20 member apart from the lamp shade; and

Fig. 3 is a vertical section of the complete device, with the closure member in place in the lamp shade.

Reference to these views will now be 25 made by use of like characters which are employed to designate corresponding parts throughout.

The lamp shade is built on a wire frame of more or less conventional construction, 30 including at least one lower ring 1 and an upper ring 2 defining the ends of the frame which are joined by suitably spaced and shaped ribs 3. The word "rings" as used here designates any shape of wire enclosure, 35 such as square, hexagonal, etc. In the upper ring 2 is mounted a spider 4 carrying a central bushing 5 through which a conductor is passed to the lamp within the shade. In the lower end of the frame is secured an inner ring 6 preferably of somewhat smaller 40 dimensions than the ring 1 and serving a purpose which will presently be described. The frame consisting of the rings 1 and 2 and the ribs 3 is covered with any suitable material 7 such as parchment or silk.

As already stated, the light issuing from the lamp within the shade is filtered, and it is therefore necessary to obstruct the light except where it is permitted to pass through 45 the filter. In accordance with these condi-

tions there is provided a closure member adapted to fit into the light-emitting end of the shade. This member consists of a sheet 8 of substantially opaque material having its edge wound on a ring 9 having a 55 configuration similar to the ring 6. The ring 9 is of a size very approximate to that of the ring 6 so that it will not pass loosely through the ring 6 but only when both rings are somewhat distorted. Inasmuch as the 60 rings are of a resilient material, they promptly resume their original configuration, whereupon the ring 6 supports the ring 9 and does not permit it to fall therethrough, as clearly shown in Figure 3.

A pair of rods 10 are secured across the ring 9, and shorter rods 11 are laid across the rods 10 and secured thereto. In the material 8 is cut an opening 12 coincident with the rectangle formed by the rods 10 and 11, and the material at the edges of this opening is wound on the rods as indicated by the numeral 13. One of the transverse rods 11 carries a pair of lugs 14 in which is journaled a hinge rod 15. The opening 12 is covered by a shutter 16 having a pair of lugs 17 lying adjacent the lugs 14 and also penetrated by the rod 15. Coil springs 18 surround the rod 15, with one end fixed thereto and the other end engaging the underside of the shutter 16 whereby the latter is normally held up against the lower face of the closure member.

The shutter in turn has a central opening 20 in which is mounted a condensing lens 21. On the incident or flat side of the lens is laid a light filter 22 held in position by means of clips 23 and consisting preferably of a flat disk of glass of a bluish tint.

Across the rods 10, at the inner side of the closure member, is supported a yoke 25 having a loop 26 in the back thereof. Behind the yoke is still another transverse rod 27 having also a loop 28 lying substantially parallel to the plane of the material 8 as clearly shown in Figures 2 and 3. The loop 26 supports a lamp socket 29 which in turn receives a lamp 30. The loop 28 supports a screw switch 31 having its terminals joined to the line 32 and 35

to the lamp socket 29 in any conventional manner.

Inasmuch as the rings 6 and 9 are of spring wire, as already indicated, they may be distorted in such a manner as to permit the closure member to be separated from the lamp shade in order to permit access to the lamp 30 in the socket 29. After the lamp has been replaced, the closure member is restored to the position shown in Figure 3 in like manner, as already stated.

Although a specific embodiment of the invention has been illustrated and described, it will be understood that various alterations in the details of construction may be made without departing from the scope of the invention, as indicated by the appended claims.

What I claim is:—

1. In combination with a lamp shade including a continuous ring member of spring material at the light-emitting end thereof, a closure member consisting of a frame member of spring material and of substantially the same dimensions as said ring member, said frame member being adapted to pass through said ring member and to be supported thereby, a substantially opaque material covering said last named frame member, and a light-modifying device inserted in said material.
2. In combination with a lamp shade including a ring member of spring material at the light-emitting end thereof, a closure member consisting of a frame member of spring material and of substantially the same dimensions as said ring member, a substantially opaque material covering said last named frame member, said material having an opening, a shutter hinged to the closure member and adapted to cover said opening, and a light-modifying device in said shutter.
3. In combination with a lamp shade including a ring member of spring material at the light-emitting end thereof, a closure member consisting of a frame member of spring material and of substantially the same dimensions as said ring member, a substantially opaque material covering said last named frame member, said material having an opening, rods laid across said last named frame member, a shutter hingedly supported by said rods and adapted to cover said opening, and a light-modifying device in said shutter.
4. A lamp shade comprising a covered wire frame, a supporting ring carried by said frame in the light-emitting end thereof, another ring adapted to be detachably supported by the first named ring, and a lens carried by the second named ring, said first named ring being set inwardly of the light-emitting end in the axial direction of said frame, whereby said lens is concealed in said end.
5. A lamp shade comprising a frame, a

supporting ring carried by said frame in the light-emitting end thereof, another ring adapted to enter said supporting ring and adapted to be detachably supported thereby, and a lens structure supported by the second named ring.

In testimony whereof I affix my signature.
CHARLES T. BRADY.
